United States Patent

Des. 236,537
Patented Aug. 26, 1975

236,537

COVER CASE FOR A CASH REGISTER OR SIMILAR ARTICLE

Arnaldo Hernandez, Fairfield, N.J., assignor to Digital
Computer Controls, Inc., Fairfield, N.J.

Filed June 17, 1974, Ser. No. 479,848

Term of patent 14 years

Int. Cl. D20—01

U.S. Cl. D52—4 A

FIG.2.

FIG.1.

FIG.3.

FIG. 5.

FIG. 7.

FIG. 4.

FIG. 6.

FIG. 1 is an isometric view of a cover case for a cash register or similar article showing my new design;

FIG. 2 is a front elevational view thereof;

FIG. 3 is a rear elevational view thereof;

FIG. 4 is a plan view thereof;

FIG. 5 is a bottom view thereof;

FIG. 6 is an elevational side view thereof; and

FIG. 7 is an elevational view of the other side thereof.

I claim:

The ornamental design for a cover case for a cash register or similar article, as shown and described.
